UNITED STATES PATENT OFFICE.

EDWARD B. BALL, OF BOSTON, MASSACHUSETTS.

SEWING-MACHINE.

SPECIFICATION forming part of Letters Patent No. 269,556, dated December 26, 1882.

Application filed January 12, 1882. (No model.)

To all whom it may concern:

Be it known that I, EDWARD B. BALL, a citizen of the United States, residing at Boston, Massachusetts, have invented certain new and useful Improvements in Sewing-Machines; and I do hereby declare that the same are fully described in the following specification and illustrated in the accompanying drawings.

This invention relates to a double race formed of a single metallic plate, grooved, as shown, on its opposite sides for the passage of the needles in different transverse planes, and to a double shuttle-carrier adapted to reciprocate two shuttles in a straight course, one on each side of said race. Its object is to enable a machine having two needles in a single needle-bar to sew simultaneously two wholly distinct and absolutely parallel and uniform seams in any fabric, and to vary the distance of such seams without any change in said race-plate.

My invention is embodied in a sewing-machine having two needles in a single needle-bar, and a vertical plate beneath its table, grooved vertically on opposite sides in different transverse planes, with two shuttles—one each side of said plate—reciprocating in a straight course in carriers running on suitable ways, the sides of said plate forming races for the two shuttles. One of the shuttles and one of the needles may be made adjustable longitudinally with relation to the other, so as to provide for entirely distinct parallel seams at varying distances from each other, as the goods pass beneath the needles in a plane transverse to that of the shuttle movement. Any suitable shuttle-reciprocating apparatus may be employed to actuate the shuttle-carriers.

The several features of my invention are specifically set forth in the appended claims.

In the drawings, Figure 1 represents a side view of the head of the machine and a vertical longitudinal section of the table, (at $y y$, Fig. 2,) showing the two shuttles with part of the double race broken away. Fig. 2 is a plan view of the double race, shuttles, and carrier, seen through the table, parts of which are broken away. Fig. 3 is a transverse section of the table, race, carriers, and sliding block, taken on the line $x x$, Fig. 2.

A is the overhanging arm, B the needle-bar,

and C C' the needles, held by a suitable clamp at the foot of said bar at the desired distance from each other, the needle C' being adjustable in various vertical notches in the clamp 55 of the bar B, in order that the seams may be correspondingly separated.

D is the table of the machine.

E is a vertical plate, extending in a straight course centrally and lengthwise of the machine, 60 and so located as to receive the needle C on one side of it and the needle C' on the other side, in grooves e and e' , respectively. There are a series of grooves e' formed to receive the needle C' in its various positions. None of 65 these grooves is directly opposite to the groove e , but they are located in different transverse planes from that groove, so that with goods passing transversely across the table D the seams will be formed parallel to each other, 70 rather than one upon the other, as would be the case with such movement of the goods if the needles reciprocated in grooves opposite to each other. The plate E $e e'$ may be cast integral with the table, but is preferably of 75 steel, to resist wear, about one-eighth of an inch thick, and held in position by insertion in vertical slots formed in lugs F beneath the table.

G G' are shuttles, mounted respectively in 80 carriers H H', which, with the construction shown in the drawings, are secured to a grooved sliding block, J, reciprocated by a connecting-rod, K, upon ways L, formed at the lower edge of the plate E, as will be clear from Fig. 3. It 85 is, however, obvious that some other form of tracks may be provided—such as parallel rods—and that the block K is not indispensable if the carriers H H' are otherwise suitably supported and connected to the shuttle-driver. 90

I make one of the shuttles and carriers longitudinally adjustable with relation to the other, that they may correspond with the positions of the needles. Such adjustment places one shuttle and its carrier slightly in advance of 95 the other, but does not separate them laterally, since they are at all times separated only by the thickness of the vertical plate E, against which each shuttle continually bears, the needles reciprocating vertically in grooves $e e'$ therein. 100 This adjustment of needles and shuttles in a plane lengthwise of the machine causes

the seams to be simultaneously formed at corresponding distances from each other in the fabric fed crosswise over the table D, as will be obvious from the drawings. The adjustability of the shuttle G' and its carrier is effected in this instance by means of a set-screw, M, which holds the carrier H' to the sliding block J, the threaded bolt having an enlarged head, I, working in a groove in the block J. Any equivalent device permitting said adjustment may be adopted. If preferred, the shuttles may be separately connected with the driving-rod K in an adjustable manner. A gage or scale for accurate placing of the carrier is desirable.

The feed-surface N should be of such breadth as may be required to correspond with the distances of the needles and seams. I also provide two presser-feet, O O', to hold the goods in position, one presser near each needle. The foot O' is laterally adjustable, so as to be placed in proper relation to the needle C' in its various positions. The means of adjustment shown are simply a perforation 25 in the presser-bar, through which is passed the horizontally-bent stem of the presser O', which may be fixed in any desired position by a set-screw or other convenient device.

I am aware that it is not broadly new to employ in a sewing-machine two or more needles and two or more shuttles, since machines embodying such features have been proposed, in which the goods were passed through in a direction parallel with the shuttle-race. 35 In some such cases the race-plate was solid, with a shuttle each side of it and a single groove for each needle directly opposite to the other groove; but there was no possibility of adjustment of the distance of the seams. 40 In other cases there were two race-plates—one for each shuttle—made adjustable toward and from each other. The essential peculiarity of my invention, as stated, is a solid vertically-grooved race-plate for both shuttles, extending 45 lengthwise of the machine and at right angles to the line of movement of the goods, the grooves e e' for the reciprocation of the adjustable needle being in different transverse planes from the groove e for the other needle. 50 (See Fig. 2.) On this plan parallel seams may be formed nearer together than is possible with any other arrangement, and the distance of such seams from each other may be varied as desired without changing the race-plate.

I claim as of my invention—

1. In a sewing-machine of otherwise suitable construction, two shuttles reciprocating in a straight course lengthwise of the machine, and a single vertically-grooved plate, E e e', as described, separating said shuttles and forming 60 a race for each, substantially as set forth.

2. In a sewing-machine, the combination of a single needle-bar carrying two needles, with two shuttles reciprocating in a straight course lengthwise of the machine, and a single vertically-grooved race-plate, E e e', as shown, forming 65 a race for each, substantially as set forth.

3. In a sewing-machine, the combination of two needles carried by one needle-bar, and two shuttles adapted to be reciprocated in a straight race lengthwise of the machine, and a single vertically-grooved race-plate, E e e', as shown, one of said needles and one of said 70 shuttles being adjustable with relation to the other, for the purpose set forth.

4. In a sewing-machine having two needles and two shuttles, the vertical plate E, forming a race for each of the shuttles, in combination with the sliding block J, the carrier H', adjustable thereon, and suitable operative mechanism, for the purpose set forth.

5. The combination, in a sewing-machine, of a single needle-bar carrying two needles, a single presser-bar carrying two pressers, and a single vertically-grooved race-plate carrying 85 two shuttles, one of said needles, pressers, and shuttles being adjustable with relation to the other, for the purpose set forth.

6. In a sewing-machine adapted to sew two seams simultaneously, the solid vertically-grooved race-plate E e e', extending lengthwise of the machine, between the shuttles, the groove e being on one side of said plate and two or more grooves, e', on the other side, but not opposite to the groove e, whereby variation of the distance of seams to be sewed is effected by adjusting the shuttle G' lengthwise of said plate and the needle C' in the corresponding groove e', substantially as and for the purpose set forth.

In testimony whereof I hereto affix my signature in presence of two witnesses.

EDWARD B. BALL.
